US0D1096234S

(12) **United States Design Patent** (10) **Patent No.:** **US D1,096,234 S**
(45) **Date of Patent:** **** Oct. 7, 2025**

(54) **PILLOW**

(71) Applicant: **Luqi Yan**, Nantong (CN)

(72) Inventor: **Luqi Yan**, Nantong (CN)

(**) Term: **15 Years**

(21) Appl. No.: **29/896,943**

(22) Filed: **Jul. 10, 2023**

(30) **Foreign Application Priority Data**

Jan. 10, 2023 (CN) 202330016814.4

(51) **LOC (15) Cl.** **06-09**

(52) **U.S. Cl.**

USPC **D6/601**

(58) **Field of Classification Search**
